UNITED STATES PATENT OFFICE

RAYMOND T. CLOUD, OF CHICAGO, ILLINOIS, ASSIGNOR TO ORCHESTRAPHONE COMPANY, OF CHICAGO, ILLINOIS, A CORPORATION OF DELAWARE

SWITCHING RELAY SYSTEM

Application filed February 4, 1928. Serial No. 252,024.

My present invention relates in general to electrical switching means, and more particularly to an electrical switch system adapted to alternately supply current to a plurality 5 of current operated devices and adapted upon each operation of the system to disconnect the source of current from one of the devices and to cause the source of current to be connected to another of the devices.

10 The object of my invention is to provide relay switching means for controlling the flow of current to two current operated devices, so that one of the devices will be connected to a current source while the other is disconnected from the source by a single closing of a given control switch and to insure that upon the next succeeding closing of the switch the operative relation of the devices to the current source will be reversed. 15

20 The present invention is particularly applicable to the reproduction of music from a phonograph having two electrical pickup means capable of reproducing music from two records alternately and provides means 25 for alternately placing the pickups in contact with the records upon the closing of a single switch, so that the music may be reproduced from either one of the records.

Other objects and advantages of my present invention will more fully appear from the following detailed description taken in connection with the accompanying drawing, which illustrates a single embodiment thereof and in which the single drawing shows 35 schematically a diagram of the arrangement of circuits and elements comprising the present invention and illustrating the same as being used in connection with two pickup devices capable of reproducing music in a phonograph having two records, each on its own rotatable turntable.

In the drawing:

Like reference characters designate similar parts throughout the several views. 45 The reference character 10 designates generally a switch adapted to be manually operated to selectively control the operation of electrical pickup devices 11 and 12 cooperable with records 13 and 14 on phonograph turntables 15 and 16.

One contact 17 of the switch 10 is connected by a conductor 18 to one side of a battery 19, the other side of which is connected by a conductor 20 to a ground connection 21. The other contact 22 of switch 20 is connected by a conductor 23 to a contact member 24 constituting part of a relay designated generally by the reference character 25. The relay 25 includes an electromagnetic coil 26 including a core 27 cooperable with an armature 28, 55 which is adapted to engage a bar 29. The bar 29 is made of insulating material and is adapted to move the contact member 24 upwardly when the coil 26 is energized. 60

One end of the coil 26 is connected by a conductor 30 to a ground connection 31. The other end of the coil 26 is connected by a conductor 32 to a contact member 33 constituting part of a relay 35, which includes 65 an electromagnetic coil 36.

The contact member 24 of the relay 25 is adapted to alternately cooperate with contact members 34 and 37. In the drawing it is shown as being in engagement with contact member 37. The contact member 37 is 70 connected by a conductor 38 to a contact member 39 comprising part of a relay designated generally by the reference character 40, which includes an electromagnetic coil 41. One end of this coil 41 is connected by a conductor 42 to a contact member 43 of a relay 75 designated generally by the reference character 45 including an electromagnetic coil 46.

The other contact member 34 associated with member 24 is connected by a conductor 80 47 to a contact 48 of the relay 45. Also connected to the contact member 24 is a conductor 49, which is connected to contact member 50 of relay 45. An intermediate portion of this conductor 49 is connected to contact 85 member 51 of relay 40.

The electromagnetic coil 36 of relay 35 has extending through it a core 52, one end of which is associated with armature 53 adapted to engage and reciprocate an insulating bar 95 54. One end of the insulating bar 54 has secured to it contact members 55 and 56 of the relay 35. The contact member 55 is adapted to cooperate with contact member 33, and the contact member 56 is adapted to cooperate 100

with contact member 57. The contact member 55 is connected by a conductor 58 to a switch 59, which is in turn connected to one side of battery 60 by a conductor 61. The other side of the battery 60 is connected by a conductor 62 to a ground connection 63. The contact member 56 is connected by a conductor 64 to contact member 65 of relay 40. The contact member 57 is connected by a conductor 66 to one end of electromagnetic coil 41 of relay 40.

Also connected to the insulating bar 54 and movable therewith is a contact member 67, which is connected by a conductor 68 to one side of battery 60 through the single pole switch 59. This contact member 67 is cooperable with contact members 69 and 70 also comprising part of relay 35. The contact member 69 is connected by a conductor 71 to one side of an electrical winding 72 comprising part of the electrical pickup device 11. The other side of the electrical winding is connected to a conductor 73, which terminates in a ground connection 74. Connected to an intermediate portion of the conductor 71 is a conductor 75, which is connected to one side of a filament lamp 76, the other side of which is connected to a ground connection 77. Thus, it will be evident that when current is flowing through coil 72, the lamp 76 will be lit.

The contact member 70 is connected by a conductor 78 to one end 79 of an electrical winding 80 comprising part of the pickup device 12. The other side of the winding 80 is connected by a conductor 81 to a ground connection 82. Also connected to the conductor 78 is a conductor 83, which is connected to one side of a filament lamp 85, the other side of which is connected to a ground connection 84. This arrangement results in the lamp 85 being lit whenever current is flowing through the winding 80.

One side of the winding 36 comprising part 45 of relay 35 is connected by a conductor 86 to the battery 60 through the switch 59. The other side or end of the coil 36 is connected to the conductor 64.

The contact member 39 of the relay 40 is cooperable with a contact member 88, which is connected to one end of a conductor 89, the other end of which is connected to one side of coil 41. Extending through the coil 41 is a core 90 cooperable with an armature 91 adapted to engage a bar of insulating material 92 cooperable with contact member 51. Obviously, when the coil 41 is energized, the bar 92 is moved upwardly so as to move contact member 51 into cooperation with contact member 88 and to disengage the contact member 88 from the contact member 39. Also connected to an intermediate portion of the insulating bar 92 is a contact member 94 cooperable with a contact member 95, both of which constitute parts of the relay 40. The

contact member 94 is connected by a conductor 96 to a ground connection 97. The contact 95 has secured to it one end of conductor 98, the other end of which is secured to one side of the coil 46 comprising part of relay 45.

The electromagnetic coil 46 of relay 45 has extending through it a core 99 cooperable with an armature 100, which is adapted to reciprocate a bar of insulating material 101. One end of this bar 101 is adapted to engage contact member 50 when the coil is energized to move the contact member 50 into engagement with a contact member 102 and to move the contact member 102 out of cooperation with contact member 48. The contact member 102 is connected by a conductor 103 to a side of the coil 46. Also connected to an intermediate portion of the bar 101 is a contact member 104 cooperable with contact member 43. This contact member 104 is adapted to be moved out of cooperation with the contact member 43 when the coil 46 is energized. Also it is to be noted that the contact member 104 is connected by a conductor 105 to a ground connection 106.

Attention is directed to the fact that I have shown a number of ground connections to indicate common return wires to the batteries and hence it is not to be inferred that such connections are essential in themselves in order to render the circuits shown operative. I find that by using these ground connections instead of common return wires that the description of the invention is greatly simplified.

As previously pointed out the reference characters 11 and 12 designate generally a pair of electrical pickup devices cooperable with phonograph records 13 and 14 on turntables 15 and 16. The turntables may be rotated by any suitable or conventional mechanism. The circuit arrangement which I have disclosed as being connected to these pickup devices permits of them to be alternately lowered into cooperation with the associated records upon each operation of the switch 10, as will be more fully explained hereinafter.

The operation of my novel switching system is briefly as follows:

Before proceeding with the description of the actual operation of my novel switch system, I shall describe briefly the operation of each of the coils of the relays 25, 35, 40, and 45. Upon the energization of coil 26, the contact member 24 is moved upwardly out of engagement with contact member 37 and into engagement with contact member 34. When the coil 36 is energized, it actuates the bar 54 to move contact member 67 out of engagement with contact member 70 and into engagement with contact member 69, and to move contact members 55 and 56 into engagement with contact members 33 and 57. The energizing of coil 41 of relay 40 results in

the armature 91 moving the bar 92 upwardly, thus causing contact member 94 to be moved out of cooperation with contact member 95 into cooperation with contact member 65 and causing contact member 51 to be moved into cooperation with contact member 88 just prior to the latter member breaking contact with member 39. Also when coil 46 of relay 45 is energized, it results in the upward movement of bar 101, thus moving contact member 104 out of engagement with member 43 and moving contact member 50 into engagement with contact member 102 just prior to the latter member being moved out of engagement with contact member 48.

After the pickup devices 11 and 12 have been placed in operative position relative to the records 13 and 14, the switch 59 is closed to connect the battery 60 to the relay circuits above described. This operation results in the energizing of the coil 80 of pickup device 12, which coil acts to allow the pickup device to be lowered into playing engagement with the record 14. It will, of course, be understood that although pickup device 11 is disposed in an operative position relative to the record 13, still it is held out of playing engagement with the record by suitable mechanism not disclosed herein until a subsequent energization of coil 72.

Now when it is desired to energize coil 72 of pickup device 11 and to de-energize coil 80 of pickup device 12, the same may be accomplished by simply closing the switch 10. A subsequent closing of this switch, however, will result in the energization of coil 80 and in the de-energization of coil 72. That is to say, subsequent operations of switch 10 results in the pickup coils being alternately energized and de-energized, thus permitting of an alternate and selective reproduction of the music on the records 13 and 14. These results are accomplished through the action of the relays 25, 35, 40, and 45 which will now be more fully described.

With the relay mechanism in the positions shown the closing of switch 10 results in the flow of current from battery 19 through conductor 23, contact members 24 and 37 of relay 25, conductor 38, contact members 39 and 88, conductor 89, coil 41 of relay 40, and to the ground connection 106 through conductor 42 and contact members 43 and 104. Obviously, the energizing of coil 41 of relay 40 operates the insulating bar 92 to move contact member 94 out of contact with member 95 and into engagement with member 65 and at the same time moves contact member 51 into engagement with contact member 88 just prior to the breaking of the engagement between contact members 39 and 88. It is to be noted, however, that the coil 41 remains energized even though contact members 39 and 88 are separated, due to the flow of current through conductor 49 connected to conductor 23. That

is to say, when the member 51 makes contact with member 88, they form a path in shunt with members 37 and 24, so that the coil 41 is held energized so long as the switch 10 remains closed, and thus prevents "fluttering" of the relay 40.

By moving contact member 94 into engagement with contact member 65, the current is caused to flow from battery 60 through coil 36 of relay 35 through conductor 64, and the contact members 65 and 94 to the ground connection 97. This results in the energizing of coil 36 of the relay 35.

Coil 36 in turn raises bar 54 to move contact member 67 out of cooperation with member 70 and into engagement with member 69 and to move contact members 55 and 56 into engagement with members 33 and 57.

The engaging of member 33 by member 55 allows current to flow from battery 60 through the coil 26 of relay 25, thus energizing coil 26. Moreover, the engaging of member 57 by member 56 will cause the coil 36 of relay 35 to remain energized after the switch 10 has been opened, and the coil 41 of relay 40 de-energized. That is to say, when the switch 10 is opened, members 65 and 94 will be separated thus preventing the flow of current from battery 60 to the ground connection 97. The current, however, will flow from battery 60 through conductor 86, coil 36, conductor 64, members 56 and 57, conductors 66 and 42, contact members 43 and 104, to the ground connection 106. This means that coil 36 will remain energized when the switch 10 has been opened as long as contact member 43 is in engagement with contact member 104 of relay 45. Subsequent operation of the switch 10, as will be more fully explained hereinafter, will result in the energization of coil 46 of relay 45, thus causing members 43 and 104 to be operated and thereby resulting in the de-energization of coil 36.

It will, of course, be noted that as long as the coil 36 of relay 35 remains energized, coil 26 of relay 25 will also remain energized.

The energizing of coil 26 of relay 25 causes bar 29 to be moved upwardly, breaking the engagement between members 24 and 37 and causing member 24 to engage member 34. Attention, however, is directed to the fact that coil 46 of relay 45 will not be energized during this operation of switch 10 due to the fact that contact member 94 has been moved out of engagement with contact member 95 by the energized coil 41.

The moving of contact member 67 out of engagement with contact member 70 and into engagement with contact member 69 results in the de-energization of coil 80 and the energization of coil 72, whereby pickup device 11 is lowered into playing engagement with record 13. Of course, it is to be under-

stood that upon the de-energization of coil 80 pickup device 12 may be removed from engagement with record 14. From the drawing it will be evident that the battery 60 supplies the current for alternately energizing the two coils 72 and 80. The energizing of coil 72 and the deenergizing of coil 80 also results in lamp 76 being lit and in lamp 85 being put out. This is accomplished due 10 to the fact that lamp 76 is in parallel with coil 72 and lamp 85 is in parallel with coil 80. These lamps are disposed in a visible position adjacent the turntables 15 and 16 and function to indicate which of the two 15 pickup devices 11 and 12 is in playing engagement with a record.

The opening of the push-button switch 10, as previously pointed out, causes the de-energization of the coil 41 of relay 40 but 20 does not de-energize the coils of relays 25 and 35. This means that the coil 72 of pickup device 11 will remain energized and the coil 80 of the pickup device 12 will remain de-energized until a subsequent operation of 25 switch 10.

Now if the push-button switch is again operated current flows from battery 19 through contact members 24 and 34, the conductor 47, the contact members 48 and 102, 30 the conductor 103, the coil 46 of relay 45, the conductor 98, the contact members 95 and 94 of relay 40, to the ground connection 97. This results in the energization of coil 46 which operates to break the connection between members 43 and 104 and to establish 35 a connection between contact members 50 and 102 as well as to break the connection between members 48 and 102. It will be noted that member 50 engages member 102 just prior to the breaking of contact between 40 member 48 and member 102. By disconnecting the members 43 and 104 the circuit from battery 60 through the relay coil 36 to ground is opened, thus resulting in a de-energization 45 of the coil 36. Obviously, if coil 36 is de-energized, coil 26 of relay 25 will also be de-energized, thereby putting the relays 25 and 35 in the positions shown in the drawing. Attention is directed to the fact that 50 even though contact members 48 and 102 are separated, still the coil 46 will remain energized due to the shunt connection established by conductor 49 between the coil 46 and the contact members 24 and 34. In other 55 words, the coil 46 will remain energized as long as the switch 10 is in a closed position.

The de-energizing of the coil 36 of relay 35 results in contact member 67 being moved out 60 of engagement with contact member 69 back into contact with member 70. The battery 60 will then be connected to coil 80 and will serve to energize the coil 80. By disconnecting the member 69 from member 67 the coil 65 72 is de-energized. Also this operation of

relay 35 acts to darken the lamp 76 and to cause the lighting of lamp 85.

The subsequent opening of switch 10 de-energizes the coil 46 of relay 45 and as a result places the relays back in the position 70 shown in the drawing. When it is desired to disconnect the source of energy from the circuit associated with the pickup devices 11 and 12, the same may be accomplished by opening switch 59.

Now, of course, it is to be understood that although I have illustrated and described in detail the preferred form of my invention, the invention is not to be thus limited, but only in so far as defined by the scope and 80 spirit of the appended claims.

I claim as my invention:

1. In an electrical switching system, electrical energy means, a pair of current operated devices adapted to be alternately connected to said means, a plurality of electrical relays, each including an electromagnetic coil associated with said devices and said energy means, the coil of one of said relays being adapted when energized to cause the energization of the coils of the other relays, an additional electrical relay including an electromagnetic coil adapted when energized to cause the de-energization of the electromagnetic coils of the other relays, and a switch 85 for alternately operating said plurality of relays and said additional relay so as to cause said relays to alternately connect the energy means to said pair of devices, whereby 90 said devices are alternately energized.

2. In an electrical switching system, electrical energy means, a pair of current operated devices adapted to be alternately connected to said means, a plurality of electrical relays, each including an electromagnetic coil associated with said devices and said energy means, the coil of one of said relays being adapted when energized to cause the energization of the coils of the other relays, an additional electrical relay including an electromagnetic coil adapted when energized to cause the de-energization of the electromagnetic coils of the other relays, and a switch 95 for alternately operating said plurality of relays and said additional relay so as to cause 100 said relays to alternately connect the energy means to said pair of devices, whereby said devices are alternately energized.

3. In an electrical switching system, electrical energy means, a pair of current operated devices adapted to be alternately connected to said means, a plurality of electrical relays, each including an electromagnetic coil associated with said devices and said energy means, the coil of one of said relays 105

- being adapted when energized to cause the energization of the coils of the other relays, an additional electrical relay including an electromagnetic coil adapted when energized to cause the de-energization of the electromagnetic coils of the other relays, and a switch for alternately operating said plurality of relays and said additional relay so as to cause said relays to alternately connect the energy means to said pair of devices, whereby said devices are alternately energized, said coil of the additional relay upon being energized being caused to remain so until said switch has been opened.
4. In an electrical switching system, electrical energy means, a pair of current operated devices adapted to be alternately connected to said means, a plurality of electrical relays, each including an electromagnetic coil associated with said devices and said energy means, the coil of one of said relays being adapted when energized to cause the energization of the coils of the other relays, an additional electrical relay including an electromagnetic coil adapted when energized to cause the de-energization of the electromagnetic coils of the other relays, and a switch for alternately operating said plurality of relays and said additional relay so as to cause said relays to alternately connect the energy means to said pair of devices, whereby said devices are alternately energized, said coil of the additional relay being adapted when energized to cause said above mentioned relay coil of said relays to become de-energized, whereby the other relay coils of said plurality of relays are also de-energized.
5. In an electrical switching system, electrical energy means, a plurality of electrical current devices designed for alternate operation, electromagnetic means for alternately connecting said devices to said energy means, and a switch associated with said energy means and said electromagnetic means for controlling the operation of said electromagnetic means, said electromagnetic means including a plurality of relays arranged in such a manner as to cause the alternate energization and de-energization of said devices upon each successive operation of said switch.
6. In an electrical switching system, electrical energy means, a plurality of current operated devices designed for alternate operation and adapted to be connected to said means for alternate energization, a plurality of electrical relays for controlling the energization of said devices, and a switch for controlling the operation of said electrical means, said electrical relays being connected to each other and to said devices in such a manner as to cause the alternate energization of said devices upon each successive operation of said switch, one of said electrical relays being adapted upon a given operation of said switch to render the other relays in-

operative, whereby one of said devices will remain energized until the next operation of said switch.

In testimony whereof I have hereunto subscribed my name at Chicago, Cook County, Illinois.
